Inventor:

Andrew R. Wall

By his Attorney

M. Ormley

UNITED STATES PATENT OFFICE.

ANDREW R. WALL, OF DAYTON, OHIO, ASSIGNOR OF ONE-HALF TO
EDWARD WALL, OF SAME PLACE.

CIDER-PRESS.

SPECIFICATION forming part of Letters Patent No. 375,028, dated December 20, 1887.

Application filed September 7, 1887. Serial No. 249,039. (No model.)

To all whom it may concern:

Be it known that I, ANDREW R. WALL, a citizen of the United States, residing at the city of Dayton, county of Montgomery, and 5 State of Ohio, have invented certain new and useful Improvements in Cider-Presses; and I do declare the following to be a full, clear, and exact description of the invention, such as will enable others skilled in the art to which it applies to make and use the same, reference being had to the accompanying drawings, and to letters or figures marked thereon, which form a part of this specification.

My invention relates to that form of cider or wine press in which the pomace is made to pass between stationary and adjustable pressure-rolls by means of an endless belt acting as a carrier. The parts and combination of parts are more particularly described hereinafter, 10 reference being had to the accompanying drawings, in which—

Figure 1 is a perspective view of the machine. Fig. 2 is a detail broken perspective view showing the swinging roller and the half-bearing and fulcrum of the weighted lever.

Similar letters refer to similar parts throughout the several views.

The letter A represents an iron roller provided with collars at each end and mounted in 15 bearings between the portions of frame-work 2 2 of my machine.

C C' are similar rollers, preferably smaller in diameter than roller A, with collars at each end and suspended on bearings between top 20 and bottom rails, 3 3 and 4 4, respectively, of the frame-work K K K of my machine.

B is a yielding or swinging pressure-roller with collars, and having its bearings in the half-bearings F' of levers F F. It is also 25 smaller in diameter than roller A, and intended to fit close to it. A canvas belt or apron, D D D, the full width of the rolls between the collars, is passed around and over the top of front roller, C', beneath large roller A, over the swinging roller B, down to and around the lower roller, C, and returns to roller C'.

F F are levers provided with half-bearings at F' F', within which roller B is suspended. 30 Levers F F are fulcrumed to frame-work 5 5 at points F'' F'', and by means of the weights W W upon levers F F the pressure of swing-

ing roller B against roller A is maintained, and the same regulated at the will of the operator.

H H are braces to hold portions of frame-work 5 5, that suspend swinging roller B.

G represents a scraper for roller A, held close to it by springs g g, to keep it clean from pomace. The scraper is hung from a partition connecting portions of frame-work 2 2, and 60 the partition also serves to separate any unpressed pomace falling on roller A from that which has been pressed coming from roller B.

Rollers A B and counter-shaft L are each provided on one end with sprocket-wheels E 65 E E, without the frame-work K K K, to engage endless chain j, by means of which, when power is applied to roller A by crank or other means, motion is communicated to roller B. Endless chain j may be hung loose, so as to 70 accommodate the varying pressure of roller B.

M represents a suitable grinding-mill hopper upon frame-work K K K, from which the apples, ground into pomace, drop upon the endless belt D D D, and carried by this apron 75 between rollers A and B the juice is pressed out onto the lower portion of the apron, and straining through it passes to any receptacle beneath. The pressed pomace is carried up over roller B and falls to the ground, to be removed at the will of the operator.

Having described my invention, what I claim, and desire to secure by Letters Patent, is—

1. In a cider-press, the combination, with 85 the larger or driving roll, of the rolls C C', a yielding pressure-roll, and the endless apron, as set forth.

2. In a cider-press, the combination, with the weighted fulcrumed levers having a half- 90 bearing, of the yielding pressure-roll, the driving-roll, the rolls C C', and the endless apron, as set forth.

3. The combination, with the driving-roll and its sprocket-wheel, of the endless chain, 95 the counter-shaft and its sprocket-wheel, the yielding pressure-roll and its sprocket-wheel, the fulcrumed weighted levers, the rolls C C', and the endless apron, as set forth.

ANDREW R. WALL.
